CLAIM

What is claimed is an ornamental design for a template for deck construction, as shown and described herein.

DESCRIPTION

FIG. 1 is a front view of a template for deck construction; FIG. 2 is a front perspective view of the template for deck construction shown in FIG. 1;

FIG. 3 is a right-side view of the template for deck construction shown in FIG. 1;

FIG. 4 is a bottom-side view of the template for deck construction shown in FIG. 1;

FIG. 5 is a top-side view of the template for deck construction shown in FIG. 1;

FIG. 6 is a back-side view of the template for deck construction shown in FIG. 1;

FIG. 7 is a front view of a template for deck construction;

FIG. 8 is a side perspective view of the template for deck construction shown in FIG. 7;

FIG. 9 is a bottom-side perspective view of the template for deck construction shown in FIG. 7; and,

FIG. 10 is a back-side view of the template for deck construction shown in FIG. 7.

The number of slots and holes may be variable (e.g., greater than or less than shown in the figures).
